COIN HOLDER

Lawrence C. Jones, Cleveland, Ohio, assignor to
The Van Dorn Iron Works Company, Cleveland, Ohio, a corporation of Ohio

Application October 11, 1949, Serial No. 5,423

Term of patent 7 years

(Cl. D52—4)

To all whom it may concern:

Be it known that I, Lawrence C. Jones, a citizen of the United States, residing at Cleveland, in the county of Cuyahoga and State of Ohio, have invented a new, original, and ornamental Design for a Coin Holder, of which the following is a specification, reference being had to the accompanying drawing, forming a part thereof, wherein:

Fig. 1 is a plan view showing the top of a coin holder, embodying my new design;

Fig. 2 is a plan view showing the bottom of the coin holder; and

Fig. 3 is an edge view of the bottom edge of the coin holder shown in Fig. 1.

I claim:

The ornamental design for a coin holder, as shown.

LAWRENCE C. JONES.
